AIR CLEANER

Herman E. Altgelt, South Bend, Ind., assignor to
 Oliver Farm Equipment Company, a corpora-
 tion of Delaware

Application September 28, 1933, Serial No. 691,287

18 Claims. (Cl. 183—16)

The present invention relates generally to air cleaners for internal combustion engines, but more particularly to an air cleaning device for vehicles such as tractors and the like.

Experience has shown that the greatest single factor which enters in the destruction and rapid wear of the operating parts of an internal combustion engine in connection with the operation of tractors is the large amounts of dust and dirt which enters through the suction of the carburetor of the internal combustion engine and for that reason various types of air cleaning devices have been developed to a certain degree, but these devices up to the present time have not been entirely satisfactory because there is no means for the operator to determine when it was necessary to remove the dirt which had accumulated in the cleaner. In other words, with air cleaners heretofore constructed, it was impossible to see whether or not the proper time had arrived to remove the dirt from the air cleaner and in most cases it is necessary to dismantle the entire air cleaner to remove the dirt therefrom. In air cleaners heretofore constructed, the manufacturer usually stipulates that the air cleaners are to be cleaned at certain definite intervals. This instruction is very unsatisfactory because the amount of dust collected in the air cleaners varies to considerable degree and is influenced by the wind, by the type of soil in which the tractor is operated and by the particular type of implement attached to or drawn by the tractor. For example, a spring tooth harrow raises considerably more dust than a braking plow. Then too, in connection with harvesting machinery, a combined harvester or grain separator, develops more dust than other types of harvesting machines.

It is therefore one of the primary objects of my invention to provide a novel and improved air cleaning device for tractor engines which will overcome all these difficulties and provide a sight gauge which will immediately notify the operator of the tractor when the accumulated dirt should be removed from the air cleaner without removing any of the parts of the same.

A further object of the invention is to provide a novel and improved air cleaning device for a tractor engine in which a single glass container forms a receptacle into which the dirt and dust is collected and which can be readily removed by the manipulation of the lever to discharge the dust and dirt therefrom without removing any of the other parts of the air cleaner.

A still further object of the invention is to provide a novel and improved liquid type air

cleaning device for internal combustion engines in which the dust and dirt collected thereby may be removed without removing the liquid from the air cleaner.

A still further object of the invention is to provide a novel and improved air cleaning device for internal combustion engines in which the dust and dirt is collected in a transparent container in combination with a lever actuated valve mechanism which permits the shutting off of the oil in the cleaner proper and allows the dirt to be removed from the transparent dirt collecting receptacle.

Another object of the invention is to provide a novel air cleaning device for internal combustion engine in which a novel arrangement of a screen covered by a dome prevents a major portion of the dirt from entering into the air cleaner.

A still further object of the invention is to provide a novel and improved construction of air cleaner in which the removable dome or cap thereof is provided with a measuring rod for measuring the oil level in the cleaner.

These and other objects are accomplished by providing a construction and arrangement of the various parts in the manner hereinafter described and particularly pointed out in the appended claims.

Referring to the drawings:

Fig. 1 is a fragmentary top plan view of the hood of a tractor having my improved air cleaner embodied therein;

Fig. 2 is a cross sectional view taken on the line 2—2 in Fig. 1;

Fig. 3 is a fragmentary cross sectional view of the valve mechanism and dirt container showing the manner in which the valve is closed and the dirt container removed therefrom;

Fig. 4 is a side elevational view of the valve mechanism and glass container;

Fig. 5 is a cross sectional view taken on the line 5—5 in Fig. 4;

Fig. 6 is a cross sectional view taken on the line 6—6 in Fig. 2; and

Fig. 7 is a cross sectional view taken on the line 7—7 in Fig. 2.

In air cleaners for the internal combustion engine heretofore constructed, both of the dry and liquid type, manufacturers give definite instructions to remove the dirt from the cleaner at frequent intervals. These instructions are very unsatisfactory because under certain conditions, air cleaners fill up with dirt in a short time, while under certain other conditions, it is not necessary to empty the dirt out of the cleaner after several

days of operation of the tractor. In other words, under favorable conditions, the dirt does not accumulate in the air cleaner rapidly while in certain other conditions, in a few hours the dirt accumulates in the cleaner to such an extent that the cleaner is unable to perform its regular function. With my improved type of cleaner, a transparent gauge or glass receptacle is provided in which the dirt collected is within clear view of the operator and at one glance it can be determined whether the dirt should be removed. This is readily accomplished by the single manipulation of the lever which releases the glass container from which the dirt can be removed and at the same time closes a valve to prevent the loss of the liquid in the cleaner.

In illustrating one form of my invention, I have shown the same in connection with a fragmentary portion of the hood 10 of a tractor in which my improved form of air cleaner is shown, in the form of a cylindrical container 11 attached to and secured to the underside of the hood, at a point substantially the center thereof, and is generally indicated by the reference character 11. Secured to the cylindrical portion 11 of the cleaner container and resting around the periphery of the bottom 12 is a coarse screen wire 13. Positioned above the screen 13 is a similar top screen 14. Compressed between these two wire screens 13 and 14 is an air cleaning fibre, generally indicated by the reference character 15. Mounted in the axial center of the cleaner proper and extending through an aperture 16 in the hood 10 and through the screens 13 and 14 as well as the fibre, 30 is an air tube, generally indicated by the reference character 17. The lower end of this air tube terminates at a point 18 above the bottom 12 of the cleaner and is also submerged below the upper surface of the liquid or oil contained in the cleaner. The level of this oil or liquid is generally indicated by the reference character 19. The air tube 17 extends several inches above the top of the hood 10 and has secured at its upward end a downwardly extending conically shaped fine mesh 40 wire screen 20. Frictionally secured to the lower ends of the fine wire screen 20 is a dome shaped or semi-spherical cap or cover 21. Secured to the center of the dome shaped cap 21 is a downwardly extending bayonet or rod 22 which extends 45 downwardly through the air tube 17 to a point short of the bottom 12 of the cleaner. The lower end of this rod 22 is notched, as shown at 23, to indicate the low level of the liquid in the cleaner and also notched, as shown at 24, to indicate the 50 high level of the liquid in the cleaner. The bottom 12 of the cleaner is provided with a central opening 23' which communicates with an angularly extending tubular bracket 24. Formed integrally with this tubular bracket 24 is a valve 55 chamber 25 which is cylindrical in form and assumes a vertical position at a point below and to one side of the cleaner proper. This valve chamber 25 is provided with a valve seat, as shown at 26. Reciprocally mounted in the upper portion of the valve chamber 25 is a valve stem 27 which has secured at its lower end, a valve 28 adapted to seat itself on the seat 26. The valve stem 27 is reciprocally mounted in a threaded collar 29 mounted in threaded engagement with the valve chamber 25 as clearly shown in Fig. 2 of the drawings. Formed integrally with the collar 29 and extending upwardly with respect thereto, is a threaded portion 30. Mounted in threaded engagement with threaded portion 30 70 is a threaded cap 31. Mounted between the

threaded cap 31 and the extension 30 is a packing washer 32. Pivoted as shown at 33, to the upper end of the valve stem 27 is a hand operating lever 34. The pivoted end of this lever is bifurcated, as shown at 35, and has the bifurcated portion engaging the opposite sides of the valve stem 27 as clearly shown in Fig. 4 of the drawings. Formed adjacent the pivoted end of the lever 34 is a cam portion as shown at 36, which is adapted to engage a washer 36' for lifting the valve stem 27 and valve 28 from its seat 26 against the action of a spring 37 mounted between the valve 28 and lower surface of the collar 29 as clearly shown in Fig. 3 of the drawings. Pivotedly connected to the pin 33 and particularly on the opposite ends 15 thereof is a substantially U-shaped bail member generally indicated by the reference character 37. The lower end of the U-shaped member 37 has a plate 38 in which is reciprocally mounted a stud 39. The upper end of the stud 39 is provided with an enlarged taper portion, as shown at 40, which is adapted to engage a recess 41 in the dirt collecting container 42. This dirt collecting container 42 is preferably made of glass so that the amount of dirt collected therein, as shown at 42', may be viewed by the operator of the tractor. The stud 39 is normally pressed upwardly by a compression spring 43 so as to resiliently maintain the glass container 42 in its position shown in Fig. 4. The stud 39 is prevented from displacement on the plate 38 by a transverse pin 44. The upper end of the glass container 42 is provided with an annular projecting flange, as shown at 45, which in turn is adapted to seat itself in an annular recess 46 formed in the lower 35 end of the valve casing 25. The glass container is sealed in this recess by felt packing 47. The clean air inlet or conduit which draws the cleaned air from the air cleaner includes an elbow 48 which in turn, has its upper end positioned adjacent to the underside of the hood 10 at a point rearwardly of the conduit or pipe 17 within the air cleaner proper. This elbow 48 extends outwardly through the cylindrical wall 11 of the air cleaner proper and is connected by a second conduit generally 45 indicated by the reference character 49 to the carburetor for supplying clean air thereto.

The operation of my improved air cleaner is as follows: Let us assume that the air cleaner is connected up in the manner shown in Figs. 1 and 2 of the drawings in which the air intake pipe extends upwardly through the hood 10 of the tractor, over which the cap or cup 21 covers a downwardly extending conically shaped screen of relatively fine mesh. This arrangement obviously 55 prevents large particles of dirt and insects from being drawn into the cleaner proper. The arrangement of the screen in this manner eliminates a considerable portion of the dirt from entering the air cleaner because the large particles drop down from the side of the cap and are carried away by the wind. The air enters through the screen 20 in the manner indicated by the arrows in Fig. 2 of the drawings, thence downwardly through the air tube 17 to the lower end 60 thereof where it passes through the oil in the bottom of the cleaner up through the oil soaked fibre into the clean air chamber above the top screen 14. From here it enters the elbow 48 located in the upper portion of the air chamber and 65 is conducted from here to the carburetor. In the operation of this air cleaner, the dirt particles which are heavier than the oil settle downwardly to the bulged or curved bottom 12 and are discharged into the angularly disposed tube 24, pass 70 75

the valve seat 26 and settle in the glass case or container 42. The lighter particles of dirt of course, remain in suspension in the oil. When the operator of the tractor observes that the dirt accumulated in the glass container 42 should be removed, the lever 34 is actuated from the position shown in Fig. 4 to that position shown in Fig. 3 in which case, the valve 28 is seated on its seat 26 in the valve casing 25. Simultaneously with the seating of the valve for stopping the discharge of oil from the cleaner, the U-shaped member is lowered to release the glass container from the recess 46 to discharge the dirt therefrom in the manner clearly indicated in Fig. 3 of the drawings. After the glass receptacle has been cleaned of accumulated dirt, it is then replaced on the beveled lug 40 of the stud 39 and the lever is actuated from the position shown in Fig. 3 to that shown in Fig. 4 in which case the glass case is secured in position and the valve 28 removed from its seat to the position shown in Fig. 2.

It will be noted in connection with my improved type of air cleaner by which the operator may observe the accumulation of dirt in the glass container so as to determine whether the cleaner should be cleaned or dirt removed therefrom, that I have also provided a measuring rod 22 which has markings thereon indicated at 23 low level and the marking 24 indicating the high level between which the amount of liquid in the container should be maintained. When the liquid is maintained at this level, it will be observed that the lower end of the tube 17 and the lower portion of the fibre is submerged to insure a complete saturation of the fibre material within the cleaner.

From the above description it will be readily seen that I have provided a novel and improved liquid type of cleaner and one in which the accumulated dirt may be seen and removed therefrom without removing the liquid therein or without dismantling any of the parts of the cleaner proper.

While in the above specification I have described one embodiment which my invention may assume in practice, it will of course be understood that the same is capable of modification and that modification may be made without departing from the spirit and scope of the invention as expressed in the following claims.

What I claim is my invention and desire to secure by Letters Patent is:

1. An air cleaner comprising a container having liquid therein, a dirt collecting receptacle detachably connected thereto, means for removing said dirt receptacle from said container without removing the liquid from said container, and means independent of said dirt receptacle for closing the communication between said container and said dirt receptacle.

2. An air cleaner comprising a container having an air cleaning liquid mounted therein, a removable dirt collecting receptacle attached thereto through which the amount of dirt collected therein may be seen, means for removing said dirt receptacle and the dirt therein without removing the liquid from said container, and means associated with said last named means and independent of said dirt receptacle for preventing the liquid from being discharged from said container when said dirt receptacle is removed.

3. An air cleaner comprising a container having an air cleaning liquid mounted therein, a dirt collecting receptacle detachably connected

at a point below said container through which the amount of dirt collected therein may be seen, and means for automatically shutting off communication between said container and said dirt collecting receptacle and for simultaneously removing said dirt collecting receptacle. 5

4. An air cleaner comprising a container having an air cleansing liquid mounted therein, said container having a curved bottom therein, a transparent dirt collecting receptacle connected 10 to the lowest point of said bottom, means for moving said dirt receptacle without removing the liquid from said container, and means operated by said last named means and independent of said dirt receptacle for preventing the discharge 15 of liquid from said container upon the removal of said dirt receptacle.

5. An air cleaner comprising a container having a liquid in the bottom thereof, an air intake extending vertically into the cleaner having the 20 lower end submerged in said liquid, a fibre material mounted in said container having the lower portion thereof submerged in said liquid, a dirt collecting receptacle attached to said container at a point below said container, and means 25 including a hand operated lever for closing the communication between said container and said dirt receptacle and for detachably supporting said dirt receptacle to said container.

6. An air cleaner comprising a container having a liquid therein, an air inlet conduit extending into said container and having its lower end submerged in said liquid, a cap detachably connected to said air inlet conduit, and a rod secured to said cap and extending through said air 35 conduit for measuring the level of the liquid in said container.

7. An air cleaner comprising a container having a liquid therein, an air inlet conduit extending thereto and terminating below the surface of said liquid, a downwardly extending conically shaped screen secured to the upper end of said inlet conduit and a semi-spherical cap substantially encasing said screen for reducing the amount of dust and dirt entering said inlet con- 45 duct.

8. An air cleaner comprising a container having a liquid therein, a valve chamber communicating with said container and located therebelow, a dirt collecting receptacle attached to 50 said valve chamber, a valve mounted in said valve chamber for closing communication between said valve chamber and said dirt collecting receptacle, and single manually operable means for controlling said valve and detachably sup- 55 porting said dirt receptacle to said valve chamber.

9. An air cleaner comprising a container having liquid therein, a valve chamber communicating with and attached to the lower portion of 60 said container, a valve mounted in said valve chamber, a dirt collecting receptacle detachably fastened to said valve chamber, a lever pivotally connected to said valve for actuating the same, and a substantially U-shaped member connected 65 to said lever for detachably supporting said dirt receptacle on said valve chamber.

10. An air cleaner comprising a container having a liquid therein, a dirt collecting receptacle detachably connected thereto, and a 70 manually operable lever for controlling the communication between said container and said receptacle and for detachably supporting said receptacle to said container.

11. An air cleaner comprising a container hav- 75

- 5   11. An air cleaner comprising a container having a liquid therein, an air inlet conduit extending into said container and having its lower ends submerged in said liquid, a cap detachably connected to said air inlet conduit, and a rod extending into said container for measuring the level of the liquid in said container. 5
- 10   12. An air cleaner comprising a container having a liquid therein, an air inlet conduit extending thereto and terminating below the surface of said liquid, a dirt collecting receptacle detachably connected to said container, said liquid extending into said receptacle, and means carried by said container for measuring the level of the liquid in said container. 10
- 15   13. An air cleaner comprising a container having a liquid therein, an air inlet conduit extending thereto and terminating below the surface of said liquid, a dirt collecting receptacle detachably connected to said container, said liquid extending into said receptacle, means for removing said dirt receptacle from said container without removing the liquid from said container and a rod extending into said container for measuring the level of the liquid in said container. 15
- 20   14. An air cleaner, comprising a container, a dirt collecting receptacle detachably connected thereto and communicating therewith, and means independent of said dirt receptacle for closing the communication between said container and said receptacle and simultaneously releasing said receptacle from said container. 20
- 25   15. An air cleaner comprising a container, air cleaning means mounted therein, a liquid mounted in said container, a removable dirt collecting receptacle attached thereto through which the amount of dirt collected therein may be seen, said liquid extending from said container into said receptacle, means for removing said dirt receptacle from said container without removing the liquid from said container, and means independent of said dirt receptacle and operated by 10 said last named means for closing the communication between said container and said receptacle. 15
- 30   16. The combination of an air cleaner formed as an integral part of an engine hood comprising a casing, and an air inlet conduit extending from above and projecting through said hood into said container. 15
- 35   17. The combination of an air cleaner formed as an integral part of an engine hood comprising a casing having liquid therein, and an air inlet conduit extending through said hood into said container and having its lower end submerged in said liquid, and means carried by said conduit for measuring the liquid level in said container. 20
- 40   18. The combination of an air cleaner formed as an integral part of an engine hood comprising a casing having liquid therein, an air inlet conduit extending through said hood into said container and having its lower end submerged in said liquid, and means carried by said conduit for measuring the liquid level in said container. 25

HERMAN E. ALTGELT. 30
